DASHPOT CONTROLLED CIRCUIT
INTERRUPTER

James M. Wallace, East McKeesport, Pa., assignor
to Westinghouse Electric Corporation, East
Pittsburgh, Pa., a corporation of Pennsylvania

Application March 30, 1950, Serial No. 152,883

7 Claims. (Cl. 200—89)

1

This invention relates to electric circuit interrupters and particularly to such interrupters having a fluid dashpot or the like, for controlling operation of the interrupter.

This application is a continuation in part of the copending application of J. M. Wallace, Serial No. 542,681, filed June 29, 1944, now Patent No. 2,528,197, October 31, 1950, on Circuit Interrupters, and assigned to the same assignee as this application. The divisional part of this application illustrates how the invention is applied to one type of automatic reclosing circuit breaker, and in addition there is also illustrated herein the manner in which this invention is applied to a circuit breaker of the type shown in the copending application of J. M. Wallace et al., Serial No. 719,524, filed December 31, 1946, now Patent No. 2,626,329, January 20, 1953, on Circuit Interrupters, and also assigned to the same assignee as this application.

It is often desirable to impose delay on circuit opening operations of a circuit interrupting device, and in the case of an automatic reclosing circuit breaker, it may also be desirable to impose delay between an opening operation and the subsequent automatic closing, all for the purpose of coordination with other circuit interrupters in the same circuit. One type of device which has desirably been employed for imposing time delay is a fluid means, such as a dashpot, because of its mechanical simplicity. However, such a time delay means has the characteristic of providing a time delay period which varies with temperature and viscosity of the fluid employed, so that proper coordination with other interrupting devices is not always obtainable under conditions of wide temperature variations.

Accordingly, one object of this invention is to provide a novel circuit interrupter having fluid means for controlling operation thereof which is not substantially affected by temperature variations.

Another object of this invention is to provide an automatic reclosing circuit breaker with fluid means controlling both circuit opening and closing operations thereof in a substantially uniform manner irrespective of temperature variations.

Another object of this invention is to provide in an automatic reclosing circuit breaker having fluid means which is rendered operative to delay operation of the breaker only in response to the occurrence of a predetermined number of closely successive operations thereof, additional means for rendering said fluid means capable of imposing a substantially constant delay period, irrespective of temperature variations.

2

Still another object of this invention is to provide temperature compensating means for circuit interrupters having fluid means controlling one or more operations thereof.

- 5 These and other objects of this invention will become more apparent upon consideration of the following detailed description of preferred embodiments thereof when taken in connection with the attached drawings, in which:
- 10 Fig. 1 is a longitudinal sectional view of a circuit breaker embodying this invention;
- Fig. 2 is a longitudinal sectional view of a modified form of circuit breaker which embodies a modified form of this invention;
- 15 Fig. 3 is an enlarged plan view of a part of the circuit breaker shown in Fig. 2; and
- Fig. 4 is a cross-sectional view of a part shown in Fig. 3, taken substantially on the line IV—IV of Fig. 3.
- 20 The embodiment of the invention illustrated in Fig. 1 is included in a circuit breaker of the type shown in J. M. Wallace Patent No. 2,333,604, issued November 2, 1943, to the same assignee of this invention, and consequently reference is hereby made to this patent for a more complete description of the circuit breaker construction and operation.

Generally, this type of automatic reclosing circuit breaker comprises, in general, a tubular casing 2 of insulating material, such, for example, as porcelain or the like, which may be supported at a mid-portion thereof, for example by a supporting bracket 4. The casing 2 illustrated, is provided with a closed lower end having an aperture for receiving a terminal bolt 6, having an enlarged head 10 positioned interiorly of the casing, and adapted to have a line conductor 8 secured thereto exteriorly of the casing.

The upper end of casing 2 is open, and is adapted to be closed by a terminal cover structure 12 having a flange adapted to be seated on the upper end of casing 2, and cover 12 may be secured to the casing in any desired manner, such, for example, as by securing means (not shown) connecting the cover to a securing ring 13 fixed to the upper end of the casing. Cover 12 is preferably hollow and may be provided with a threaded filler plug 14, and with a wire connector 15, for connection to another circuit conductor. Within hollow cover 12 there is provided a supporting shaft 16 extending transversely thereof and mounted at its opposite ends in opposite walls of the hollow portion of the cover, for supporting a generally U-shaped spring support 18. Spring support 18 preferably has the leg portions thereof rotatably mounted on shaft 16,

and a lockout spring 20 is coiled about shaft 16, and has one end 22 thereof reacting against the bight portion of spring support 18, with the other end 24 thereof reacting against a part of cover 12, to bias spring support 18 in a counterclockwise direction about the shaft 16. However, spring support 18 is normally prevented from rotating counterclockwise on shaft 16 by an overcenter toggle, comprising pivotally connected toggle levers 26 and 28 which are pivoted to spring support 18 and to cover 12, respectively. Toggle lever 28 is fixed on a rotatable shaft 30 for pivotally mounting toggle lever 26 on the casing and toggle levers 26 and 28 are held at the overcenter position shown in full lines in Fig. 1, by an indicating handle 32 which is also rigidly mounted on shaft 30, and engages an adjustable stop screw 34 mounted beneath a hood 35 integral with cover 12. The outer end of handle 32 is provided with a hook eye aperture 36, so that it may be actuated by a hook stick operating member or the like.

Shaft 16 within the hollow portion of cover 12 also supports a reclosing spring 37 of smaller diameter and mounted within lockout spring 20, with one end 38 of this spring reacting against the bight portion of spring support 18, and with the other end 40 of the reclosing spring reacting against an actuating lever 42 which is pivotally mounted on shaft 16. The breaker contacts are adapted to be actuated at least to close the circuit by spring 37 and actuating lever 42, and for this purpose the lever is connected to a contact actuating rod 46, by means of a pair of connecting links 44 of insulating material, such, for example, as fiber or the like. Contact actuating rod 46 extends through casing 2, passing through a solenoid coil supporting frame 48 and into an arc chamber 50 located adjacent the closed lower end of the casing. All of the parts within casing 2 are supported from cover 12, since coil supporting frame 48 is secured to the cover by spaced supporting posts 52 of insulating material, such, for example, as fiber or the like, and arc chamber 50 is supported from coil supporting frame 48 by spaced supporting plates 54 (only one shown), which are secured to frame 48 and to arc chamber 50. The lower end of arc chamber 50 is provided with a terminal cap 56 threadedly mounted thereon, and a coil compression spring 58 of conducting material, is adapted to be compressed between terminal cap 56 and head 19 of terminal bolt 6, when cover 12 is assembled in operative position with the casing, to conduct current from terminal bolt 6 to terminal cap 56.

Arc chamber 50 is preferably formed by a tube 60 of insulating material, such as fiber or the like, and has, in addition to terminal cap 56, an upper cap 62 threadedly mounted on the upper end thereof. Terminal cap 56 of the arc chamber is provided with a contact screw 64 substantially centrally thereof, and also has a plurality of inlet openings 66 adapted to be controlled by a valve ring 68 freely movable between terminal cap 56 and the adjacent end of tube 60. Upper cap 62 for the arc chamber is provided with at least one outlet opening 72 adapted to be controlled by a valve plate 74 movable between the upper end of tube 60 and cap 62, but normally held at a position uncovering opening 72, by a coil compression spring 76.

Contact actuating rod 46 is provided with an end section 78 which extends through a central aperture in arc chamber cap 62, and section 78 is provided with a sheath 80 of insulating mate-

rial, such, for example, as a molded insulating material, for engagement with the aperture in cap 62. Section 78 of the contact rod is provided with a contact head 82 at its outer end for engagement with fixed contact screw 64.

Because of the particular construction of arc chamber 50, when movable contact 82 is moved away from fixed contact 64 to strike an arc, such an arc will create pressure within the arc chamber such as to cause valve disk 68 and valve plate 74 to close both the inlet and outlet openings. Preferably casing 2 is filled with an arc extinguishing liquid, such as oil, up to the level L shown in Fig. 1, so that arc chamber 50 will be submerged in such liquid and will always be filled with liquid. Accordingly, an arc formed within chamber 50 will cause deterioration of the arc extinguishing liquid, and form gases to further increase the pressure within the chamber. This pressure within the chamber acts on section 78 of the contact actuating rod, together with its sheath 80, in a piston-like manner to aid in moving contact 82 away from fixed contact 64, and may even cause overtravel of the movable contact with respect to its actuating mechanism. As soon as the arc is extinguished, pressure will drop within the arc chamber, and spring 76 will be operative to move valve plate 74 to a position uncovering outlet opening 72. This will permit the gas bubble formed within the arc chamber during arcing to escape from the upper end of the chamber, and the head of liquid outside the arc chamber will cause valve disk 68 to be displaced, thereby permitting fresh liquid to flow in through inlet openings 66. This provides an automatic flushing of arc chamber 50 after each circuit interrupting operation, during reclosure of the breaker contacts by reclosing spring 37.

In order to cause an initial separation of movable contact 82 from fixed contact 64, which is at least sufficient to establish an arc within the arc chamber, there is provided a solenoid coil 84 mounted within the supporting frame 48. This coil is annular in form, and is provided with a dashpot sleeve 86 which extends through the center of the coil, with the sleeve preferably being of an insulating material such, for example, as a molded insulating material. Dashpot sleeve 86 is held in engagement with a cup-shaped washer member 90 reacting against the top of frame 48, by engagement of a cross frame member 88, which is integral with supporting plates 54. A tubular core 92, of any desired magnetic material such as iron or the like, is provided for coil 84, and the core is slidably mounted within dashpot sleeve 86 and has a close fit therein to act as a dashpot piston. The lower end of core 92 is preferably closed and provided with a central aperture for closely slidably receiving contact actuating rod 46, and has vent apertures 93 through the side wall thereof adjacent the closed lower end. Core 92 is provided with an internal wear ring 94 adjacent the other end thereof having a close sliding fit with an enlarged portion 96 of an actuating sleeve 98 which is slidably mounted on contact actuating rod 46. Actuating sleeve 98 is provided with a flange 100 at the upper end thereof above frame 48, for engagement with a shoulder 101 on the contact actuating rod. A coil compression spring 102 reacts between the closed end of solenoid core 92 and the enlarged portion 96 of actuating sleeve 98, to bias the core to the lower position shown in Fig. 1.

In order to hold the contacts separated to prevent too rapid a reclosure thereof following a

circuit interrupting operation, contact actuating rod 46 has mounted thereon a transversely extending supporting plate 104, and a latch plate 106 is pivotally mounted at one end on this supporting plate. Latch plate 106 is provided with an aperture for receiving contact actuating rod 46 which is large enough to permit pivotal movement of the latch plate, and with another aperture adjacent its mounting on supporting plate 104, for relatively closely receiving a latch rod 108 supported between frame 48 and cap 62. Latch rod 108 is provided at the lower end thereof with a portion 110 which is reduced in section, for a purpose to be described, and latch plate 106 is normally biased upwardly by a compression spring 112.

The electrical circuit through the breaker illustrated in Fig. 1 extends from connector 15 on cover 12, by way of a conductor 114 to solenoid coil 48, then by a flexible conductor 116 to contact actuating rod 46, to fixed contact 64, conducting spring 58, then to terminal bolt 6 and line conductor 8. It is thus apparent that solenoid coil 84 is connected in series in the circuit through the breaker so that it will be responsive to currents above a predetermined value to attract core 92 upwardly into the coil, while compressing spring 102. This movement of core 92 will be delayed due to the dashpot action thereof in dashpot sleeve 86, and will not cause separation of the contacts because spring 102 is considerably weaker than closing spring 37. When core 92 finally engages the lower end of actuating sleeve 96, the latter will be moved upwardly into engagement with shoulder 101 on actuating rod 46, to cause separation of contact 82 from fixed contact 64. This establishes an arc in arc chamber 50, which is extinguished as previously explained, and due to the lost motion of core 92 on the contact actuating rod, pressure within the arc chamber may cause overtravel of contact 82 and contact actuating rod 46, beyond the point to which it is moved by core 92. During opening movement of contact 82, latch plate 106, which is carried up with contact actuating rod 46, slides over latch rod 108, and any tendency of latch plate 106 to bind on latch rod 108 is overcome by pivotal movement of the latch plate in a clockwise direction, while compressing spring 112. However, as soon as the arc is extinguished and reclosing spring 37 attempts to move contact 82 towards fixed contact 64, latch plate 106 will bind on latch rod 108 due to counterclockwise rotation thereof under the influence of spring 112. In order to release latch plate 106, it is necessary to depress the free end of the plate to rotate it in a clockwise direction. This is done by solenoid core 92 during its return movement under the influence of gravity and compression spring 102. However, return movement of solenoid core 92 is quite slow, because of the dashpot action of the core in sleeve 86, and consequently movable contact 82 will return substantially at the same speed as core 92, until latch plate 106 arrives at reduced portion 110 of latch rod 108 where it can no longer bind on the latch rod, and at this point contact 82 will be rapidly moved into engagement with fixed contact 64 by reclosing spring 37. It should be noted that in a circuit opening operation, movement of solenoid core 92 upwardly is delayed by its dashpot action in sleeve 86 only until ring 93 reaches the upper end of enlarged portion 96 of the actuating sleeve. Thereafter liquid trapped in the upper end of the sleeve 86 may escape through the core and its vent open-

ings 93, so that the final movement of core 92 into engagement with actuating sleeve 86 to separate contact 82 from fixed contact 64 takes place rapidly, to obtain at least a predetermined separation of the contacts on each circuit interrupting operation at a relatively rapid rate.

Lockout means are provided for counting the number of closely successive circuit interrupting operations, such as a lockout piston and cylinder 118 mounted on coil supporting frame 48, which is adapted to be actuated by a lockout pawl 120. The pawl 120 is tiltably and slidably mounted on a guide rod 121, and is adapted to be actuated by flange 100 on actuating sleeve 86 each time it moves upwardly during a circuit interrupting operation, to advance the lockout piston, until after a predetermined number of closely succeeding circuit interrupting operations, the piston is finally advanced sufficiently to engage toggle lever 28 adjacent the knee of the toggle to move the toggle levers overcenter, and thereby permit lockout spring 20 to rotate spring support 18 counterclockwise. This causes the bight portion of spring support 18 to engage an extension 119 on actuating lever 42 to also rotate the actuating lever counterclockwise and hold the breaker contacts in open circuit position. It will be observed that counterclockwise rotation of spring support 18 removes the reaction point for end 33 of reclosing spring 37, so that this spring will be inoperative to reclose the contacts. When the toggle formed by levers 26 and 28 is moved overcenter and breaks, handle 32 rotates with lever 28 in a clockwise direction and extends below hood 35 to give a readily visible indication of the lockout condition of the breaker. The breaker will remain in a lockout position until manually reset by operation of handle 32 back to the position shown in Fig. 1, wherein toggle levers 26 and 28 are moved back to the overcenter position shown, to prevent operation of lockout spring 20.

The parts of the breaker described thus far are substantially all more particularly disclosed in the aforementioned Wallace patent.

One difficulty with dashpot time delay means, especially those designed to operate in a liquid, such as oil, is the variation in time encountered with temperature variations due to the change in viscosity of the oil with such temperature changes. It is of particular importance in automatic reclosing circuit breakers that the time of operation, including both opening and reclosing of the contacts, be a predetermined value which does not substantially vary, due to the necessity of coordinating such circuit breakers with other circuit interrupting apparatus, such as fuses and other circuit breakers having definite time characteristics.

In order to improve the time characteristic of the dashpot time delay means described above, the upper end of dashpot sleeve 86 is provided with vents which are opened gradually in response to a decrease in temperature and consequent increase in viscosity of the arc extinguishing fluid. For this purpose, a closure disk 136 is threaded into the upper end of coil supporting frame 48, and has threadedly mounted in a central aperture thereof, a plug 138 adapted to be held in engagement with a shoulder provided in the upper end of frame 48. Plug 138 is provided with a plurality of channels 140 communicating the upper end of sleeve 86 with the space within cup washer 90. Closure disk 136 extends across the open side of cup washer 90

and is provided with vent apertures 142, communicating the space within cup washer 90 with a space 144, provided within the upper end of frame 48. The space 144, in turn, opens to the interior of casing 2 by means of vent apertures 146, preferably aligned with the vent apertures 142. Both sets of vent apertures 142 and 146 are adapted to be controlled by a bimetal valve disk 148, mounted in space 144. Bimetal valve disk 148 is provided with a central aperture for freely receiving plug 138, so that the valve disk is freely movable to cover and uncover vent apertures 142 and 146. Bimetal valve disk 148 is constructed in a well-known manner of laminations 150 and 152 intimately secured together as by welding or the like. Lamination 150 of the disk is of a material having a relatively high coefficient of thermal expansion, such as brass, and the other lamination 152 is of a material having a relatively lower thermal coefficient of expansion, so that at normal temperatures the disk 148 will be substantially flat, as shown in Fig. 1, and will assume an upwardly concave shape upon lowering of the temperature. Valve disk 148 is positioned below the level of arc extinguishing fluid within casing 2, so that it is responsive to the temperature of such liquid to more or less cover vent apertures 142 and 146.

During operation of the circuit breaker, if it be assumed that the arc extinguishing liquid is at a normal temperature so that valve disk 148 is in a flat condition, as soon as solenoid core 92 moves upwardly, it will cause a flow of fluid through vent apertures 142 and move valve disk 148 upwardly to cover vent apertures 146, and the rate of movement of core 92 will be governed by the rate of escape of fluid trapped in the upper end of dashpot sleeve 86 through the relatively small clearances between the core, sleeve 86, and enlarged sleeve portion 96. Now, if the temperature of liquid within casing 2 drops so that its viscosity increases, valve disk 148 will assume an upwardly concave curved shape, so that when core 92 moves upwardly, there will be an additional path opened for fluid to escape, through vent openings 142 and through the central opening in valve disk 148 and out vent openings 146, even though the valve disk be moved up by the flow of fluid outwardly into engagement with the upper wall of space 144. Similarly, upon return movement of core 92, valve disk 148 will be drawn down to cover vent openings 142 if the valve disk is in a flat condition, but if it is curved, an additional path for the flow of fluid into the upper end of dashpot sleeve 86 will be provided through vent openings 146, and around the outside edge of the valve disk and through vent openings 142 and channels 140 into the dashpot sleeve, to thereby compensate, both during circuit opening and circuit closing, for any increase in viscosity of the arc extinguishing liquid, by increasing the openings for inflow and outflow of liquid with respect to dashpot sleeve 86.

The modification shown in Figs. 2 to 4 is illustrated in connection with a circuit breaker of the general type disclosed in the aforesaid Wallace et al. application, which is mounted in a metal tank 141 having a closed bottom wall and an open top. Preferably, the tank is adapted to be lined at least over the bottom wall and up to a point adjacent the open top of the container with a liner 143 of insulating material such as fiber, or the like, and is adapted to be filled with an insulating liquid, preferably a liquid having arc extinguishing ability, such as oil or the like up to

the level L. The upper end of tank 141 is provided with an outwardly extending flange 145 on which the flange 147 of a cover casting 149 is adapted to be seated, preferably, with a gasket 151 interposed therebetween. Flange 145 of cover casting 149 may be provided with an integral lip 153, and the cover may be secured to the tank in any desired manner, such for example, as by bolts (not shown) extending through openings in cover flange 147 and secured to suitably formed brackets on the tank.

The breaker contacts and certain of the contact actuating mechanism are adapted to be supported in tank 2 from cover casting 149 by means of a pair of integral supporting lugs 154 (only one shown) depending from the top wall of the cover casting and each is adapted to be secured to a spacer rod 156 of insulating material which in turn is secured to a supporting casting 158. A supporting plate 160 may be supported in a similar manner from casting 158, so that a solenoid coil 162 may be mounted between casting 158 and supporting plate 160, with the central opening in the coil aligned with openings provided in casting 158 and plate 160.

Spaced stationary contacts 164 of the breaker are each supported from plate 160 by supports 166 of insulating material, such as fiber, formed in a U shape, with the stationary contacts being mounted in openings provided in the base portions 168 of each support 166, and with the upper ends of each support 166 having laterally extending flanges 170 by means of which each support is secured to supporting plate 160. As illustrated, each contact 164 is formed as the head of a bolt to which a conductor may be secured, as by the nuts 172.

Stationary contacts 164 are adapted to be closed by engagement therewith of a bridging contact 174 having contact tips 176 at opposite ends thereof for engagement with the stationary contacts, respectively. Bridging contact 174 is supported substantially centrally thereof on a slide contact actuating rod 178 by a pivot pin 180 for limited pivotal movement about a transverse axis. Contact rod 178 being mounted for longitudinal sliding movement through coil 162 and the aligned openings in plate 160 and casting 158, it will be observed that bridging contact 174 is free to adjust itself to the stationary contacts by restricted pivotal movement about its pivotal mounting 180. Contact rod 178 should be of an insulating material such as fiber or a molded insulating material.

The upper end of contact actuating rod 178 has a pair of connecting links 182 positioned at each side thereof and pivoted thereon as by a pivot pin 184, with the upper ends of these connecting links mounted on a common pivot pin 186 for a pair of toggle levers 188 and 190. Toggle levers 188 and 190 are both formed of sheet material, with lever 188 bent to substantially channel form with outwardly extending flanges 192 adapted to be received at the free end thereof in recesses 194 provided in the spaced downwardly depending fingers of an angled supporting bracket 196 which, in turn, is secured as by a screw 198 to a lug 200 integral with the cover casting. Preferably, the base of the channel part of toggle lever 188 is extended as at 202 through the space between the supporting fingers of bracket 196, and at the other end of lever 188 the sides of the channel formation thereof are extended to be mounted on pivot pin 186. A coil tension spring 204 has one end hooked into an

opening provided in toggle lever 190, and has the opposite end thereof hooked over an integral spring support (not shown) on the cover casting.

It will be observed that in the closed circuit position of the breaker illustrated in Fig. 2 of the drawings, the line of action of toggle spring 204 is below the pivot supporting recesses 194 for toggle lever 188, and accordingly, the toggle spring acts to bias bridging contact 174 into engagement with stationary contacts 164 of the breaker, under a predetermined pressure. However, as soon as contact operating rod 178 moves upwardly to separate the bridging contact from the fixed contacts of the breaker, toggle lever 188 will pivot about recesses 194 and the line of action of toggle spring 204 will thus be caused to approach that pivot point so that in response to a very small contact separation the line of action of toggle spring 204 will pass through pivot recesses 194 which is the on-center position of the resilient toggle arrangement comprising toggle levers 188 and 190 and toggle spring 204. As a practical matter, the opening movement of the contacts necessary to move toggle levers 188 and 190 to the on-center position mentioned above may be made very small, in one operative device being on the order of one-quarter of an inch. When toggle levers 188 and 190 reach their on-center position referred to above, further relative movement of the two toggle levers in the same direction is prevented because the upper edge of toggle lever 190 engages the base of the central channel formation of toggle lever 188. Moreover, since the point at which toggle spring 204 is hooked into lever 190 then substantially coincides with recesses 194 in which toggle lever 188 pivots during contact opening movement, it will be apparent that the remainder and major part of contact opening movement will occur substantially uninfluenced by toggle spring 204. Substantially the reverse of the above operation occurs when contact operating rod 178 moves downwardly to close the circuit from the full open contact position, because during the first and major part of contact closing movement levers 188 and 190 will be in engagement so that such movement will be uninfluenced by toggle spring 204. However, as soon as pivot 186 passes below a line drawn from the remote end of toggle spring 204 through pivot recesses 194 for link 188, toggle spring 204 will then be effective to move the toggle levers toward the position shown in Fig. 2, and the force exerted by toggle spring 204 thus tending to close the contacts will continue to increase as toggle levers 188 and 190 move further away from their on-center positions.

Solenoid coil 162 previously mentioned is adapted to be energized under certain conditions for automatically opening the circuit breaker contacts. The central opening through coil 162 preferably is provided with a cylindrical sleeve 206 in which a solenoid core 208 is adapted to be slidably mounted in a piston-like manner. Core 208 is in the form of a cylindrical sleeve having opposed slots 210 in the upper portions thereof adapted in the normal closed circuit position of the device illustrated to extend partly above and partly below supporting plate 160, by engagement of an exterior shoulder adjacent the upper end of the core with a sleeve 212 which has an external rib held between the sleeve 206 for the coil and supporting plate 160. The lower end of core 208 is provided with opposed holes 214, for a purpose to be hereinafter described.

A contact actuating sleeve 216 is telescoped over

contact actuating rod 178 and its lower end is received in core 208 and threadably mounted therein. A coil compression spring 218 is provided within actuating sleeve 216 on contact actuating rod 178 and is adapted to react between an inner shoulder in the core and a pin 220 extending transversely through actuating rod 178.

The circuit through the circuit breaker thus far described may now be traced from the point where it enters tank 141 through one of a pair of terminal bushings 222 (only one being shown), with each bushing secured to cover casting 149 as by bolts 224, and each being provided with a terminal fixture 226 at the upper end thereof mounted on a conductor element which extends through the bushing and emerges from a reduced extension 228 of the bushing seated in an opening provided in the top wall of cover casting 148, and proceeds by conductor 230 directly to one fixed contact 164 of the breaker. When the contacts are in engagement, the circuit then proceeds through bridging contact 174 to the other fixed contact 164, and then by way of a conductor 232 to one terminal of solenoid coil 162. The other terminal of coil 162 is adapted to be connected by a conductor 234 to the conducting means in the other terminal bushing 222. It will be apparent that solenoid coil 162 in this embodiment of the invention is connected in series in the circuit through the circuit breaker so as to be energized at all times dependent upon the value of the load current flowing in the circuit.

For any given rating of circuit breaker, solenoid coil 162 is designed to become sufficiently energized when the load current in the circuit exceeds its rating as to attract core 208 and move it upwardly. Assuming the upper end of sleeve 206 to be closed except for the small clearance between sleeve 216 and casting 158, so that substantially no fluid can escape, core 208 will move upwardly relatively rapidly until the bottom of slot 210 reaches sleeve 212, whereupon there is no longer any vent for fluid contained in cylindrical sleeve 206, and it then becomes necessary upon further upward movement of core 208 to displace the liquid in sleeve 206 above the core through the relatively small clearance between the core and sleeves 212 and 216 and between sleeve 216 and casting 158. Accordingly, opening movement of the core will be slowed up by the aforesaid dashpot action an amount determined by the current value of the overload, and, therefore, an inverse time-current characteristic on opening is obtained. This is due to the fact that the force exerted on core 208 by coil 162 will vary substantially directly in accordance with the value of overload current, and consequently the greater force exerted on higher currents will result in less time delay than on lower values of overload currents. Finally, when the upper ends of holes 214 clear the upper edge of sleeve 212, core 208 will no longer be restrained by the dashpot action because fluid may then relatively freely escape, and the final opening movement thereof may be relatively rapid. As soon as core 208 commences its upward travel, bridging contact 174 being held engaged by toggle spring 204 does not move, so that spring 218 is compressed until the energy stored in it is sufficient to overcome the force exerted by toggle spring 204, at which time contact actuating rod 178 will start to move upwardly. As soon as actuating rod 178 moves upwardly, the force exerted by toggle spring 204 begins to decrease and in a very short distance

has substantially no value at all, so that the remaining major part of the circuit opening movement of the bridging contact 174 is easily effected by expansion of spring 218. However, flange 236 is provided to obtain a positive contact separation in the event there is any sticking or welding of the bridging contact to stationary contacts 164. In either case, it is apparent that toggle levers 188 and 190 will be moved to their on-center position in the manner previously described, and bridging contact 174 will be moved by spring 218 to its full open circuit position. When the contacts separate and an arc is struck, with the resultant pressure developed thereby in the region beneath core 208, it will be observed that washer 238 will be moved upwardly to seat on the lower end of core 208 to close off the clearance space between core 208 and rod 178 and thus prevent gases and other contaminating elements developed by the arc from entering dashpot sleeve 206.

When the breaker contacts have attained their full open circuit position, the parts associated therewith are biased to return by gravity. This closing bias is relatively light and will be immediately opposed by the dashpot action of core 208. Accordingly, the return movement will be relatively slow until pivot point 186 moves below the line of action of toggle spring 204 when toggle levers 188 and 190 are in engagement, whereupon bridging contact 174 will be rapidly moved to effect a snap-action closing of the breaker contacts by toggle spring 204. Moreover, at about this same time the lower ends of slots 210 in core 208 will clear the lower edge of sleeve 212 so as to vent the dashpot comprising sleeve 206 and core 208.

In order to provide means for maintaining the breaker contacts separated and to also provide for manual operation thereof, spring means are provided for holding the breaker contacts open, which means can be manually actuated. This means comprises a toggle lever 240 having a slot 242 at one end thereof for receiving a pin 244 mounted between spaced supporting arms 246 integral with cover casting 149. The other end of toggle lever 240 is pivoted, as by a pivot pin 248, to the adjacent end of a second toggle lever 250, and this, in turn, is mounted on a pivot pin 252 intermediate its ends, with the pin 252 mounted on the adjacent wall of cover casting 149. A slot 254 is provided through the cover casting 149 for receiving the other end of toggle lever 250 which acts as a manual operating handle at the exterior of the circuit breaker casing, being provided with a hook eye 256 in its outer end. A coil compression spring 258 is mounted on toggle lever 240 and reacts between washers mounted on the toggle lever, one of which engages supporting pin 244, and the other of which engages a shoulder located adjacent pivot 248. Normally, toggle levers 240 and 250 are held with pivot 248 below the center line connecting pins 244 and 252, with the outer end of lever 250 positioned in and beneath an integral hood 251 on cover casting 149, in engagement with an adjustable stop screw 260 mounted in the hood.

In the position of toggle levers 240 and 250 illustrated, they have no effect on operation of the circuit breaker as previously described, being normally inactive in this respect. However, the common pivot pin 248 of toggle levers 240 and 250 is extended at one side toward toggle levers 188 and 190 and in the normal position of the parts extends beneath the adjacent flange 192 of

toggle lever 188. Accordingly, if it is desired to manually open the circuit breaker contacts, a hook stick or similar operating member may be inserted in hook eye 256 of toggle lever 250 and pulled downwardly to rotate the toggle lever in a counterclockwise direction about its supporting pivot 252 to move toggle levers 240 and 250 over-center in an upward direction, and in doing this, the common pivot pin 248 engages the adjacent flange 192 of toggle lever 188 and moves it upwardly in a counterclockwise direction, thus carrying contact actuating rod 178 with it to separate bridging contact 174 from stationary contacts 164. The contacts will be held open by spring 258 which maintains toggle levers 240 and 250 in their upper overcenter position. In thus manually opening the circuit after toggle spring 204 is moved to its on-center position, it will be observed that the spring 258 of toggle lever 104 is only required to maintain the contacts of the breaker open against the relatively light closing bias due to gravity. With the breaker contacts maintained at their open circuit position following the manual circuit opening operation described above, it will be apparent that the outer end of toggle lever 250 projects below hood 251 of cover casting 149 so as to provide a readily visible indication that the breaker contacts are maintained at open circuit position. It will further be apparent that the breaker contacts may then be closed only by manual operation of toggle lever 250 in the opposite direction, that is, by exerting an upward force on the outer end of the toggle lever to rotate it in a clockwise direction to move it and toggle lever 240 back overcenter to the position illustrated in the drawings. This manual operation of toggle lever 250 does not directly close the breaker contacts but merely permits closure of the contacts in the manner previously described.

An integrating mechanism for automatically moving toggle levers 240 and 250 upwardly over-center and thus preventing reclosure of the circuit breaker only in response to a predetermined number of closely successive circuit interrupting operations, and at the same time for automatically controlling the circuit opening and closing times in a predetermined manner in any sequence of a plurality of closely successive circuit opening operations, is provided comprising a cylindrical tube 259 is clamped in a lateral extension of casting 158 at the top of solenoid coil 162, and this tube has a plug 262 threaded into the lower end thereof with the plug having a small central opening controlled by a ball-check valve 264, which permits flow of fluid into the lower end of tube 259 but prevents outflow. An integrating piston 266 is mounted in tube 259 and normally rests on the upper end of plug 262, being provided with a reduced extension 263 at the upper end thereof, having a plurality of spaced circular flanges 270 forming rack teeth thereon, and having an elongated insulating extension 272 on the extreme outer end thereof which is positioned below an extension 274 on toggle lever 240. A pawl lever 276 is pivotally mounted at one end as at 278, with this end of pawl lever 276 being split with legs located at each side of tube 259 and with pivot 278 supported on spaced supporting flanges 280 integral with casting 158.

Pawl lever 276 has a connecting web intermediate its ends, and at the other end thereof the sides of the lever are extended outwardly and laterally as at 282, to normally be in engagement with a washer 284 mounted on actuator

ing sleeve 216 in engagement with a shoulder adjacent the outer end of this tube. Pawl lever 276 is normally biased into engagement with washer 284 by a coil tension spring 292 hooked over the remote edge of the web of the pawl lever at one end and anchored to an ear integral with casting 158 at its other end. Pawl lever 276 is provided with a pawl member 288 pivoted thereon as at 290, and biased by a spring 292 in a counterclockwise direction to a position wherein a portion of pawl member engages the connecting web of pawl lever 276.

In order to control the opening and closing times of the circuit breaker contacts to provide for different opening and closing times on predetermined circuit opening and closing operations in any sequence of closely successive operations, as on continuing overloads, the dashpot formed by sleeve 206 and solenoid core 208 has a vent 294 at the upper end thereof which is annular in form being provided in casting 158 about actuating sleeve 216. Annular vent 294 communicates with a laterally extending passage 296 also formed in casting 158, so that fluid may escape from the upper end of sleeve 206 through annular vent 294 and passage 296, and then through a pair of opposed openings 298 in tube 259 from whence it may escape through a discharge opening 300, also formed in casting 158. The openings 298 in integrator tube 259 are aligned with passage 296 and discharge opening 300.

In order to compensate for the effect of temperature changes on the action of the fluid time delay means in this embodiment of the invention, passage 296 in casting 158 is provided with a tapped opening (Fig. 4) adapted to receive a plug 302 containing a thermal valve arrangement. The plug 302 has a reduced threaded extension 304 adapted to be threadedly received in the tapped opening of casting 158. The reduced inner end of plug 302 has a central passage formed therethrough for receiving a check valve member in the form of a rivet 308 having a head 313 adapted to be seated on an internal shoulder formed in the reduced extension 304 of the plug. Check valve member 308 has a small central passage 310 formed therethrough for a purpose to be described. The outer enlarged end 306 of plug 302 is internally threaded for threadedly receiving a partition disk 312 which is threaded into engagement with an internal shoulder formed in the enlarged outer end 306. Partition 312 is formed with diametrically opposed outlet openings 314, and the passage of fluid through these openings is controlled by a valve disk 316 mounted beneath partition 312, and having a plurality of openings including relatively small openings 318 at diametrically opposed positions, and large openings 320 of substantially the same size as outlet openings 314 in the partition, and also located at diametrically opposed positions with all of the openings in valve 316 located on the circumference of the same circle as openings 314 in partition 312, and with such circle having its center on the central axis of plug 302. Valve disk 316 is mounted for rotation by means of a valve stem 322 secured centrally thereof and projecting through an opening in partition 312 to have secured at its outer end one end of a spiral bimetal element 324, the other end of which is secured to a stationary post 326 secured in partition 312.

With the parts of the circuit breaker at their normal positions illustrated in Fig. 2, it will be

apparent that when the circuit breaker operates to open the circuit, the upper end of dashpot sleeve 206 being open through annular vent 294, passage 296, openings 298 and discharge opening 300, that solenoid core 208 will be moved very rapidly upwardly since the liquid in dashpot sleeve 206 above the core may be freely vented through the vent passages mentioned above, and consequently the initial circuit opening operation of the breaker will occur substantially instantaneously. As solenoid core 208 moves upwardly, washer 284 will be carried upwardly with actuating sleeve 216 and thus carry the free end of pawl lever 276 upwardly with it to move pawl member 288 into engagement with the upper one of flanges 270 on integrating piston 266, to thus carry the piston upwardly a predetermined distance throughout opening movement of sleeve 216, and due to interlocking of the pawl lever and flange 270, no overtravel of piston 266 is possible. Integrating piston 266 is not, however, carried upwardly a distance sufficient to entirely remove reduced portion 268 thereof from between openings 298 in cylinder 258, so that the vent passageway from the upper end of dashpot cylinder 206 will not be blocked off by integrating piston 266. When the breaker recloses following such a first circuit interrupting operation, such reclosure will also occur extremely rapidly because core 208 does not have any dashpot action in its dashpot sleeve 206 due to the upper vent for the sleeve still being open. Accordingly, the first opening and reclosing of the circuit breaker contacts will both occur substantially instantaneously with no time delay interposed due to the dashpot action of core 208 in dashpot sleeve 206. During reclosing of the breaker the first time, integrating piston 266 is left at the position to which it was advanced, since pawl member 288 is free to disengage the circular flanges 270, and if the breaker remains closed, integrating piston 266 will slowly reset to the position shown, this resetting movement being relatively slow due to the necessity of displacing liquid drawn into the lower end of cylinder 258 by advancement of piston 266 during the opening operation, past the relatively small clearance between cylinder 258 and piston 266. This means, of course, that if an overload appears on the circuit at a later time, the breaker contacts will then be substantially instantaneously opened and closed in the manner described above. However, if the breaker immediately reopens after a first opening and reclosing operation, pawl member 288 this time will engage the next lower circular flange 270 on the integrating piston 266 and raise the piston a further amount sufficient to bring the piston between side openings 298 in integrator cylinder 258 so that the integrating piston acts as a valve to close off the vent passage 296 from the upper end of dashpot cylinder 206. Inasmuch as the integrating piston 266 does not close the vent passage until core 208 is substantially at the end of its circuit opening movement at which time the core vents dashpot sleeve 206, this second closely successive circuit opening operation will, like the first, occur substantially instantaneously with substantially no delay due to dashpot cylinder 206 and core 208. However, on the succeeding reclosing operation, integrating piston 266 having closed the vent at the top of dashpot cylinder 206, this reclosing operation will be delayed in the manner previously described by the dashpot action of core 208 in cylinder 206.

This second reclosing operation will result in leaving piston 266 at the further advanced position described above, from which it eventually will reset in the manner previously described if the breaker remains closed, so that an overload appearing on the circuit at a later time will result in the breaker operating in the manner described above for the first and second closely succeeding circuit opening and closing operation. However, in the event the overload continues after the second closely succeeding circuit opening and closing operations, the breaker will again open, and this time the opening operation will be delayed by the dashpot action of core 208 in dashpot sleeve 206, since integrator piston 266 has not had time to recede from the position to which it was advanced on the second opening operation of this series of closely succeeding circuit opening operations, where it blocks the vent passage from the upper end of dashpot sleeve 206. A vent opening 299 is preferably provided in cylinder 259 to prevent fluid being forced through the clearance space between piston 266 and cylinder 259 and into the bottom of cylinder 259 beneath piston 266 during a time delay circuit opening operation, and thereby preventing undesired advancement of piston 266 at such time. The circuit closing operation of the breaker following the third opening will be delayed in the manner previously described, inasmuch as such third opening operation results in further advance of integrator piston 266 where it still blocks the vent passageway from the upper end of dashpot sleeve 206. The breaker may then continue to open and reclose if the overload continues, with each opening and closing being delayed by the dashpot action of core 208 in dashpot sleeve 206 until finally pawl member 288 advances integrator piston 266 an amount sufficient to cause the upper extension 272 thereof to engage the extension 274 of toggle lever 240 and move this lever upwardly overcenter so that toggle spring 258 will maintain the contacts separated in the manner previously described. It is thus apparent that toggle levers 240 and 250 will be automatically moved upwardly overcenter to maintain the breaker contacts separated only in response to a predetermined number of closely successive circuit opening and closing operations, usually four such operations, however, in the event a lesser number of closely successive opening and closing operations occurs, the integrating mechanism will reset and the breaker contacts will be automatically held open only when the predetermined number of opening and closing operations occurs in close succession. Obviously, after the breaker contacts have been automatically actuated to a position where they are held open by toggle spring 258, they can be reclosed only by manual operation of toggle lever 250 in the manner previously described.

When the breaker contacts are held open in the manner described above, it will be apparent that integrator piston 266 is held at its uppermost position by pawl lever 276 which is held at its upper position by actuating sleeve 216. Accordingly, when the breaker is manually reclosed, the first inrush of current may be of a value in excess of the rating of the breaker, but since this current is due mainly to the sum of the starting currents of apparatus connected on the circuit, it will be of short duration and it is not desirable that the breaker should open on such initial high currents. Accordingly, it will be observed that when the breaker is manually closed following

automatic operation to be held open, integrator piston 266 will be at a position where it blocks the vent passage from the upper end of dashpot sleeve 206, so that any attempted opening operation of the breaker will be delayed by the dashpot action of core 208 in dashpot sleeve 206. This delay is long enough to permit the high value of starting currents encountered on reclosing the circuit to be dissipated, so that solenoid core 208 will reset before it has moved upwardly far enough to cause the breaker contact to open. Integrator piston 266 will also gradually reset and eventually be restored to the position shown in Fig. 2, so that when an overload comes on the circuit at a later time, it can operate in the manner described above to permit the circuit breaker to open and close the circuit, the same predetermined number of times before the breaker contacts are maintained open, and it will control the times of predetermined circuit opening and closing operations in any such sequence of closely succeeding opening and closing operations in the same manner. In the preferred sequence of operations leading to the breaker contacts maintained in open circuit position mentioned above, that is, a sequence of four operations in number, it will be apparent that with the apparatus described above, the first two opening operations will occur substantially instantaneously and the second two opening operations will be delayed with an inverse time-current characteristic due to the dashpot action of core 208 in dashpot sleeve 206. Moreover, the reclosing times in any such sequence of four closely successive opening and closing operations will comprise a first substantially instantaneous closing operation with the remaining circuit closing operations being delayed by the dashpot action of core 208 in dashpot sleeve 206. The only time that the first circuit opening is delayed is when such an operation occurs immediately following manual reclosing of the contacts after they have been automatically held open.

A protective gap device 301 of the expulsion type may be provided to prevent operation of the breaker on voltage surges, with the outer tube of the protective device mounted intermediate its ends on an extension 311 of supporting plate 160 at the underside of solenoid coil 162, being secured thereto as by nuts threaded on the arrester tube. One terminal of the protective device may be connected with conductor 232 and one terminal of solenoid coil 162, with the other terminal of the protective device (not shown) connected with the other terminal of coil 162 and conductor 234. This protective device and its particular manner of mounting and connection with this type of apparatus is more particularly disclosed and claimed in the copending application of H. L. Rawlins and J. M. Wallace, Serial No. 694,074 on Overvoltage Protective Devices, filed August 30, 1946, now Patent No. 2,550,124, Apr. 24, 1951, and assigned to the same assignees of this invention.

It will be observed that the thermally operated valve shown in Figs. 3 and 4 operates in a manner somewhat similar to that shown in the embodiment of the invention illustrated in Fig. 1 in that it controls a vent passage for the dashpot controlling circuit opening and closing operation of the circuit breaker when the valve formed by integrator piston 266 is in its closed position where the dashpot becomes effective to perform its delaying functions. Thus, the thermal valve shown in Figs. 3 and 4 includes a valve member

316 which is loosely mounted so that when dashpot piston core 208 rises during a circuit opening operation valve disk 316 will be forced into engagement with partition 312 to thus seal off the outlet openings 314 in the partition (assuming a relatively high temperature with the valve positioned by bimetal element 324 as shown in Figs. 3 and 4). During a circuit opening operation, check valve rivet 308 cannot exert any fluid restriction because any tendency to do so would result in movement of this member upwardly to unseat its head from the shoulder inside reduced extension 304 of plug 302. However, when dashpot piston core 208 descends during a circuit closing operation, valve disk 316 will be moved back to the position shown in Fig. 4 where outlet openings 314 in partition 312 are uncovered, and check valve 308 will then settle down to seat its head on the internal shoulder in extension 304 of the plug so that the rate of closing movement will be determined by the size of passage 310, which in turn will determine the rate of flow of fluid into dashpot sleeve 206. Bimetal element 324 is, like element 148 shown in Fig. 1, formed of a strip of laminated material, with the lamination having the greater coefficient of expansion arranged at the outside of the spiral formation. It will be apparent then that upon the occurrence of lower temperatures of the fluid in tank 141, bimetal element 324 will act to rotate valve disk 316 in a clockwise direction as viewed in Fig. 3, to first align small openings 318 with outlet openings 314 in partition 312, and as the temperature further decreases to ultimately align one or both pairs of large openings 320 with the outlet openings 314 to thus compensate for the increased viscosity of the fluid accompanying such lowered temperatures.

From the foregoing it is believed apparent that there is disclosed herein two modifications of means for rendering two forms of circuit breakers employing fluid time delay means substantially constant in their timing periods, irrespective of variations in temperature. It will thus be apparent that these fluid controlled circuit breakers can thus be more readily made to coordinate with other circuit opening means connected in the same circuit with them which have time characteristics substantially unaffected by temperature variations. Both forms of the particular temperature compensating means disclosed herein are arranged so that they are exposed to the fluid contained within the circuit breaker casing, which fluid is also employed to assist in extinguishing the arcs formed when the circuit breakers open. Moreover, both forms of temperature compensation employ check valve like members operated by pressures developed in fluid dashpots to control vent openings from the dashpot, with the extent of such control being determined by the extent of deformation of a bimetal construction. In the embodiment of the invention shown in Fig. 1, the temperature compensation applies to both circuit opening and circuit closing operations, whereas that shown in Figs. 2 to 4 applies only to the circuit opening operation, because it is the time delay imposed on this operation which is most important in obtaining proper coordination with other circuit opening apparatus.

Having described preferred embodiments of the invention in accordance with the patent statutes, it is desired that the invention be not limited to these particular constructions, inasmuch as it will be apparent, particularly to

persons skilled in the art, that many modifications and changes may be made in these structures without departing from the broad spirit and scope of this invention. For example, the particular fluid control means disclosed may be employed with still other forms of circuit breakers. Accordingly it is desired that this invention be interpreted as broadly as permitted by the prior art.

10 I claim as my invention:

1. In an automatic reclosing circuit breaker, a casing adapted to contain an arc extinguishing fluid, separable contacts in said casing, electromagnetic means in said casing for separating said contacts to interrupt the circuit in response to a predetermined electrical condition of the circuit, means for automatically reclosing said contacts in response to a circuit interrupting operation, fluid time delay means utilizing said arc extinguishing fluid for controlling movement of said contacts, said time delay means including an enclosure having a vent at one end and variable vent means including temperature responsive means providing the vent of said time delay means with a variable orifice offering substantially the same resistance to movement at all temperatures.
2. In an automatic reclosing circuit breaker, a container for an arc extinguishing fluid, separable contacts disposed in said container, means in said container for separating said contacts to interrupt the circuit in response to a predetermined electrical condition of the circuit, means for automatically reclosing said contacts in response to a circuit interrupting operation, fluid dashpot means utilizing said arc extinguishing fluid for controlling operation of said contacts, said dashpot means having at least one vent opening located beneath the level of said fluid, check valve means movable into engagement with said vent opening by fluid displaced by said dashpot means during a circuit opening operation and movable away from said vent opening by fluid attempting to enter said dashpot means during a circuit closing operation, including a bimetal element responsive to temperature conditions so that said valve means is movable in a different direction responsive to the temperature of said fluid to vary the extent it covers the vent opening during a circuit opening operation.
3. In an automatic reclosing circuit breaker, a casing adapted to contain an arc extinguishing fluid, separable contacts located in said casing, means in said casing for separating said contacts to interrupt the circuit in response to a predetermined electrical condition of the circuit, means for automatically reclosing said contacts in response to a circuit interrupting operation, fluid dashpot means utilizing said arc extinguishing fluid for controlling operation of said contacts, said dashpot means including an enclosure having at least one vent opening adjacent one end thereof and located beneath the level of said fluid, check valve means movable into engagement with said vent opening by fluid displaced by said dashpot means during a circuit opening operation and movable away from said vent opening by fluid attempting to enter said dashpot means during a circuit closing operation, said valve means being movable in a different direction to vary the extent it covers the vent opening during a circuit opening operation, and bimetal actuating means responsive

to the temperature of said fluid for moving said valve means in said different direction.

4. In an automatic reclosing circuit breaker, a casing adapted to contain an arc extinguishing fluid, separable contacts in said casing, electro responsive means in said casing having a movable armature for separating said contacts to interrupt the circuit in responsive to a predetermined electrical condition of the circuit, means for automatically reclosing said contacts in response to a circuit interrupting operation, fluid dashpot means including said armature and utilizing said arc extinguishing fluid for controlling operation of said contacts, said dashpot means having vent means comprising opposed inner and outer openings located beneath the level of said fluid, check valve means movable into engagement with said outer vent opening by fluid displaced by said dashpot means during a circuit opening operation and away from said inner vent opening, and movable away from said outer vent opening by fluid attempting to enter said dashpot means during a circuit closing operation and into engagement with said inner vent opening, said check valve means including a temperature responsive element so that at least the part of said valve means engageable with said outer vent openings is movable in a different direction in response to the temperature of said fluid to vary the extent it covers the vent opening during a circuit opening operation.

5. In an automatic reclosing circuit breaker, a casing adapted to contain an arc extinguishing fluid, separable contacts in said fluid, means in said casing for separating said contacts to interrupt the circuit in response to a predetermined electrical condition of the circuit, means for automatically reclosing said contacts in response to a circuit interrupting operation, fluid dashpot means utilizing said arc extinguishing fluid for controlling operation of said contacts, said dashpot means having vent means comprising opposed inner and outer openings located beneath the level of said fluid, check valve means movable into engagement with said outer vent opening by fluid displaced by said dashpot means during a circuit opening operation and away from said inner vent opening, and movable away from said outer vent opening by fluid attempting to enter said dashpot means during a circuit closing operation and into engagement with said inner vent opening, and a bimetal element connected to said valve means to move it in a different direction in response to the temperature of said fluid to vary the extent it covers the vent opening during a circuit opening operation.

6. In an automatic reclosing circuit breaker, an arc space adapted to be filled with an arc extinguishing fluid, separable contacts adapted when separated to draw an arc in said space, means for separating said contacts to interrupt the circuit

in response to a predetermined electrical condition of the circuit, means for automatically reclosing said contacts in response to a circuit interrupting operation, fluid dashpot means utilizing said arc extinguishing fluid for controlling operation of said contacts, said dashpot means having a pair of separate vent means located beneath the level of said fluid, a normally open valve for one of said vent means, means for counting the number of operations of said breaker which occur in close succession, means operated by said counting means for closing said normally open valve after a predetermined number of operations of the breaker in close succession, and a thermally responsive valve member for the other vent means to vary the flow of fluid therethrough in accordance with the temperature of said fluid.

7. In an automatic reclosing circuit breaker, an arc space adapted to be filled with an arc extinguishing fluid, separable contacts adapted when separated to draw an arc in said space, means for separating said contacts to interrupt the circuit in response to a predetermined electrical condition of the circuit, means for automatically reclosing said contacts in response to a circuit interrupting operation, fluid dashpot means utilizing said arc extinguishing fluid for controlling operation of said contacts, said dashpot means having a pair of separate vent means located beneath the level of said fluid, a normally open valve for one of said vent means, means for counting the number of operations of said breaker which occur in close succession, means operated by said counting means for closing said normally open valve after a predetermined number of operations of the breaker in close succession, a thermally responsive valve member for the other vent means to vary the flow of fluid therethrough in accordance with the temperature of said fluid, and said thermally responsive valve member comprising check valve means movable into engagement with said vent opening by fluid displaced by said dashpot means during a circuit opening operation and movable away from said vent opening by fluid attempting to enter said dashpot means during a circuit closing operation, and said valve means being movable in a different direction in response to the temperature of said fluid to vary the extent it covers the vent opening during a circuit opening operation.
